United States Patent Office.

ALBERT H. MERSHON, OF PHILADELPHIA, PENNSYLVANIA.

Design No. 2,973, dated March 31, 1868.

DESIGN FOR FURNACE-DOORS.

The Schedule referred to in these Letters Patent and making part of the same.

TO ALL WHOM IT MAY CONCERN:

Be it known that I, ALBERT H. MERSHON, of the city of Philadelphia, and State of Pennsylvania, have originated and designed a new Pattern for Furnace-Doors, of which the following is a full, clear, and exact description, reference being had to the accompanying photograph, making part of this specification.

The design includes the draught-doors A A', poke-door B, and feed-door C, hinged to the frames D and E in their usual relation one above the other. The draught-doors A A' are elliptical, the poke-door B rectangular, the feed-door C rectangular on the bottom and sides and curved at the top to conform to the curved top of the upper frame E. In the centres of the feed-door C and poke-door B are circular revolving draught-plates. From the centre of each door radiate alternate convex and concave corrugations, rounding off at the ends to the inner face of the doors. A moulding, F, finishes the edges of the faces of the frames D and E.

What I claim as my invention, and desire to secure by Letters Patent, is—

The design for furnace-doors herein set forth and shown.
